UNITED STATES PATENT OFFICE.

FRANK G. MARBACH, OF CLEVELAND, OHIO, ASSIGNEE TO THE CHAMPION REGISTER COMPANY, OF CLEVELAND, OHIO, A CORPORATION.

COMBINED PRINTING AND AUTOGRAPH MACHINE.

1,247,305.

Specification of Letters Patent. Patented Nov. 20, 1917.

Application filed February 5, 1917. Serial No. 146,659.

To all whom it may concern:

Be it known that I, FRANK G. MARBACH, a citizen of the United States, residing at Cleveland, in the county of Cuyahoga and 5 State of Ohio, have invented certain new and useful Improvements in Combined Printing and Autograph Machines, of which the following is a specification.

This invention pertains to a combined 10 printing and autograph machine, and the object of the invention is to provide a machine or device by means of which a grocer or other merchant can print his own memorandum blanks or forms in duplicate or 15 triplicate progressively with their use and note his sales on the printed blank as he does now upon the usual hand pads, all substantially as shown and described and particularly pointed out in the claims.

20 In the accompanying drawings, Figure 1 is a plan view of the complete machine, and Fig. 2 is a side elevation thereof. Fig. 3 is a longitudinal sectional elevation of Fig. 1, but with certain parts shown also in dotted 25 lines. Fig. 4 is a cross section on a line corresponding to 4—4, Fig. 3. Fig. 5 is a sectional detail of the front top portion of the machine and showing portions of the top plate and the tablet plate partially raised. 30 Fig. 6 is an elevation of the printing roll and the platen roll in working relations and partially sectioned. Fig. 7 is a detail of the type tube or cylinder for the printing roll. Fig. 8 shows a diagrammatic view 35 more or less in perspective of the three paper rolls and the paper drawn out from each and in position relatively as seen in Figs. 1 and 3, but with the printing means omitted.

As thus shown and described the machine 40 is seen to be of a dual character, being, first, and essentially a printing machine of a mani-folding type and adapted to use carbon surface to make all the impressions, and also having a desk, tablet or table on which to 45 make memoranda on the superimposed sheets or strips of paper with their blanks printed as they come from the printing rolls, the carbon on some of the strips serving the double purpose of printing the blank and 50 making the autograph entries by pencil through the lower sheets or blanks, so that two or more copies of the entries may be obtained.

In the drawings, 1 represents the casing 55 of the machine in or upon which the several

working parts are mounted and the comparatively small proportions of the machine may be judged from the size of the printed blanks which are of the usual merchant's pad size. The said working parts comprise 60 a type or printing roll 2 and a platen or bed roll 3 in working relations therewith relatively as seen in Figs. 1 and 3. The platen roll has trunnions or spindles adapted to rest removably in suitable fixed bearings 5 in the sides of the casing and the printing roll has spindles resting in the tops of the standards 6, which are pivoted at their lower ends on or over the removable false bottom *d* of the casing and engaged at 65 their top and rear by thumb screws 7 in end plate 8 to govern their working relations to or with the platen roll, to the end that the two rolls shall coöperate to make the printed impressions clear and uniform. 70 The said end plate 8 is pivotally supported at its bottom on casing 1 and is locked in upright position by overlapping flange 9 on top plate 10, which is pivoted at 12 at the front of the machine and adapted to be 75 raised and lowered on its pivot as the use of the machine may require. The said top plate or cover has a recess or opening at its front end through which the writing plate, tablet or table 13 is exposed and of a size 80 proportioned to the printed blank, and the superimposed sheets or layers of paper to be written upon are carried along mechanically between said plates 10 and 13 and exposed through said recess to make notations 85 thereon.

Obviously, the printing of the memorandum blanks must precede their actual use, and it will be seen that I have provided in this machine for triplicate or three-fold 90 strips or sheets to be printed in the same operation between the rolls 2 and 3, the printing roll, of course, determining the size and the style of the blank and presumably corresponding in these respects generally to 95 hand-pads as they are commonly used.

I have further provided that one of the said strips or sheets shall be perfectly plain or white on both sides and the other two each provided with a carbon side and a 100 plain side respectively. The white sheet comes at the bottom to the writing pad in the present arrangement and the carbon slips or sheets above the same and all are 105 arranged to be fed through the press 110

- together and that both carbon slips will be printed on their plain sides while the white paper slip or strip is printed on only one side. To these ends I employ three suitable 5 spools 14, 15 and 16, respectively, for the three rolls *a*, *b* and *c* of paper wound or placed thereon, and which spools are supported on standards 17 on false bottom *d* of the casing or body of the machine.
- 10 The white paper strip *a* being inside on spool 14, it passes around the platen roll and the next is carbon-roll *b* carried on spool 15 with its carbon next to the white strip and thus make a distinct carbon print 15 thereon. The characters or letters on the printing roll strike through all the strips to the platen 3 and therefore make plain imprints on all, but the strip on roll *c* is placed on spool 16 with the carbon inside and the 20 white outside, and it unwinds reversely as to roll *a* and *b*, so as to get the carbon printing effect thereon as well as upon the sheet *b*. To these ends I carry the said strip *c* first upward around the printing roll to its 25 rear which brings the carbon outside over said roll, and then the sheet is run down behind roll *c* and around three several idlers 20, 21 and 22 apart from said roll and up again between the two rolls where the said 30 strip is carried forward with the other two strips in overlapped relations one upon the other and with the carbon sides so exposed that all three sheets are printed alike on their white sides. It should be especially 35 observed that sheet *c* exposes its white side to its own carbon side over the printing roll and also prints sheet *b* by its carbon exposure.
- Thus the white side of strip *c* is exposed 40 to its own carbon outside around the printing roll, while the white side of strip *b* is exposed to the carbon side of strip *c* and the strip *a* to the carbon side of *b*. The said idlers for strip *c* are supported at their ends in the standards 23 and may be mere rods over which the paper is adapted to slide.
- Operation of the said rolls 2 and 3 is by means of a crank 24, pinion 25 therewith and small gear 26 meshed by said pinion and transmitting through gear 27 on said platen roll and which in turn engages gear 28 on the printing roll, thus providing a positive actuation for said rolls and by which the paper sheets are fed along. An additional feed roll 30 at the front of the machine is provided in this connection and driven by a sprocket chain 31 engaged therewith and with a sprocket wheel 32 on the spindle or trunnion on the platen, or by equivalent 60 means. An idler roll 33 cooperates with roll 30 in drawing the paper strips along, and this operation is timed with the pushing effect at the rear through the mutually geared rolls 2 and 3 so as to keep the sheets stretched as they are carried along to be

written upon. Further feed on the paper to make an additional imprint carries the memorandum sheets forward over the end of the machine as seen in Figs. 1 and 3, and they are torn off together across the sharp 70 blade or edge 33'. Thus the slips or blanks are printed as fast as they are used and another set of blanks is printed as the machine is operated to discharge the last set used.

The type or printing roll 2 has a tubular printing form 35 of cylindrical shape, Fig. 7, which is a distinct article of manufacture and removably sleeved and clamped on the body of said roll as also plainly shown in 80 Fig. 6. It is important that the said form or cylinder should fit closely and uniformly on said body and be firmly secured at its ends to do good work, and to these ends the said form or tube is beveled at its end edges 85 38 and adapted to fit beneath the correspondingly undercut flanges or edges 39 on the said body at one end and on the ring-shaped clamping nut 36 at the other end, and which nut is threaded on the relatively enlarged base portion of the spindle 37 and serves to clamp the said tube end-wise. With this construction the said tube may be split and yet be locked in close fitting relation on the roll. 95

The platen roll 3 has a similar construction in detail, having a tube or cylinder 40 of rubber, lead or other suitable material fitted thereon and provided with beveled ends 41 engaged beneath the undercut flanges 42 on said body and on the nut 43 respectively, and said nut is threaded on the enlarged base of the spindle or journal 44. The said printing cylinder or tube 35 is interchangeable with others having different 105 forms according to the work to be done.

What I claim is:

1. A machine as described, having a printing roll and a platen roll, in combination with a plurality of spools for paper strips 110 adapted to be fed through said rolls together, and means to pass one of said strips of paper reversely through said rolls and with both sides thereof exposed between the rolls. 115

2. A machine as described having a printing roll and a platen roll, a series of spools for rolls of paper strips comprising one or more strips with carbon sides and plain sides respectively, and means to carry one 120 of said carbon sided strips first around the said printing roll and then between said rolls with the other strips to be printed therewith.

3. A machine as described having a printing roll and a rotatable platen therewith, a series of spools for rolls of paper strips and a set of idlers about the rear roll of said series so disposed that the paper strip on said roll will unwind at the rear and pass first 125 130

around said printing roll and thence around said idlers and up between the said rolls.

4. A machine as described having a printing roll and a platen roll, standards having 5 said printing roll mounted in the upper ends thereof and pivoted at their lower ends, and an end plate and cover constructed to support said standards and roll in working position.
- 10 5. A machine as described, having a printing roll and a platen roll, pivoted standards supporting said printing roll, a pivoted end plate and set screws therein bearing against the upper ends of said 15 standards and a cover plate confining said end plate.
6. A machine as described, comprising a printing roll and a platen roll, and a plu-

rality of spools adapted to deliver paper therefrom to said rolls, and means to reverse the sides of the paper delivered from one of said spools before it reaches said rolls. 20

7. A machine as described, an inclosing casing, a printing roll and a platen roll within the top of said casing, supports for 25 said printing roll pivoted in the bottom of the casing, and adapted to be swung rearward outside the casing to remove the said roll and an end plate on said casing provided with means to hold said supports and 30 roll in working position.

Signed at Cleveland, in the county of Cuyahoga, and State of Ohio, this 1st day of February, 1917.

FRANK G. MARBACH.
